UNITED STATES PATENT OFFICE.

MARSHALL B. LLOYD, OF MENOMINEE, MICHIGAN, ASSIGNOR TO THE LLOYD MANUFACTURING COMPANY, OF MENOMINEE, MICHIGAN, A CORPORATION OF MICHIGAN.

DESIGN FOR A COLLAPSIBLE FRONT HOOD FOR GO-CARTS.

43,148.

Specification for Design.

Patented Oct. 15, 1912.

Application filed April 28, 1910. Serial No. 558,313. Term of patent 14 years.

To all whom it may concern:

Be it known that I, MARSHALL B. LLOYD, a citizen of the United States, residing at Menominee, in the county of Menominee and State of Michigan, have invented a new, original, and ornamental Design for Collapsible Front Hood for a Go-Cart, of which the following is a specification, reference being had to the accompanying drawing, forming a part thereof.

Claim:

The ornamental design for a collapsible front hood for a go-cart as shown.

In testimony whereof, I have hereunto set my hand, this 20th day of April, 1910, in the presence of two subscribing witnesses.

MARSHALL B. LLOYD.

Witnesses:

HILDA C. PETERSON,
MARGARET J. BRESNAHAN.
